UNITED STATES PATENT OFFICE.

FRANCIS ALEXANDER LUKS, OF ALBERT PARK, VICTORIA, AUSTRALIA.

DRAFT THROAT FOR FURNACES.

Application filed July 10, 1924. Serial No. 725,223.

To all whom it may concern:

Be it known that I, FRANCIS ALEXANDER LUKS, a subject of the King of Great Britain and Ireland, residing at 14 Albert Road, 5 Albert Park, in the State of Victoria, Commonwealth of Australia, have invented certain new and useful Improvements in Draft Throats for Furnaces; and I do hereby declare the following to be a full, clear, and 10 exact description of the invention, such as will enable others skilled in the art to which it appertains to make and use the same.

I provide an improved and economical draft throat for use in combination with 15 the firebridge in a furnace for the purpose of promoting more complete combustion than is usual, and for reducing the production of smoke to a minimum, or approximately so. My draft throat is a portable 20 article of manufacture, the form and interior and exterior dimensions of which are fixed, subject to such provisions as may exist for adjustments, before the throat is installed in the firebridge, and the result 25 is that the installation is rendered easy and speedy of accomplishment, the danger that workmen will err in the formation in fire-bridges of draft passages of prescribed dimensions being avoided,—and other advantages are also secured.

My improved draft throat is of suitable metal, or like suitable material—metal being, compared with firebrick, lighter, easier to transport, and less easily fracturable; 35 and during use, with proper care, suitable metal will retain a reasonably smooth surface for a very long time, and will stand frequent cleanings to remove foulings, and secure full efficiency of operation. My 40 throat made of suitable metal, even while it is heated as the result of use, will withstand the shocks due to the use of cleaning irons, and the firebridge will not require to be repaired at short intervals. It is thus 45 advantageous to make metal throats, standardizing them to suit the principal demands, and having them ready for transport and installation.

In the drawings herewith Figure 1 is a 50 perspective view of one of my firebridge throats ready for installation, the inlet being open.

Figure 2 shows, diagrammatically, and 55 on a smaller scale, a longitudinal section through a boiler furnace having my draft throat.

The draft throat has at its base 1 a sufficiently broad inlet opening 2, shown as wide as the throat—and it has means 3—shown as a flap door—for regulation of 60 the operative area of the inlet opening during use. This opening acts well when it is of about the full width available in the space 4 below the grate 5, in which it will be located for the reception of heated air 65 and gases, with some quantity of fine solid matter when the latter is present therein.

This inlet passage extends forwardly a short distance in the throat base 6; the passage way then extends upwardly within 70 the throat body 7 which has walls which gradually converge, so that the upper part 8 of the throat is relatively narrow. The front and back walls 9 and 10 of the body 7 are shown converging as stated, and the 75 effect is to somewhat choke the draft and produce acceleration of its speed, so that the draft will be discharged from the throat top under pressure.

There is at 11 means of discharge of the 80 air and gases from the throat top into the furnace 12. I provide in addition when desirable a throat hood 13, which has a frontal opening so that it will deflect the escaping draft forwardly. The said hood 85 13 definitely prevents descent of furnace flames into the throat.

It suffices however in many cases to rely 90 on the natural forward draft in the furnace.

Firebridge and furnace designs vary considerably in practice; hence this invention is not limited to the forms illustrated, precisely.

The inlet 2 should be well beneath the fire 95 bar inner end 14; the throat head should be at or near the top 15 of the firebridge which will be built to contain the said throat and will be made of suitably refractory material.

The draft inlet control flap 3 has pivotal supports, 16 being apertured bars which receive the ends of a flap top bar 17; connected to the flap is a control rod 18, which extends outside the furnace, as through a 100 hole 19 in the front 20, and has a handle, and setting notches 22, there being a stop 23 conveniently situated, with which to engage any desired notch, to adjust the flap 105 and regulate the draft into the throat and thus its delivery into the combustion chamber 12.

I claim:

In a furnace fire bridge, a built-in metal draft throat having a forwardly extending base inlet of about the full width of the fire bridge base and having its inlet end about flush with the face of the rear wall of the fire bridge, an upwardly extending body formed integral with the base portion and having converging front and rear walls 10 and a laterally continuous outlet in the fire bridge body, the width of said throat being uniform from the inlet to the outlet; a deflecting removable hood controlling the outlet and formed with a curved wall serving

to cause discharge of the draft forwardly 15 into the furnace, a pair of brackets carried by the aforesaid body and projecting from the rear wall of the fire bridge, a flap for controlling the inlet having its other edge supported from said brackets and an adjustable pull rod extending from the flap to the exterior of the furnace. 20

In witness whereof I have hereunto set my hand.

FRANCIS ALEXANDER LUKS.

Witness:

GEORGE G. TURRI.
